[57] CLAIM

The ornamental design for an article carrier bracket, as shown and described.

DESCRIPTION

FIG. 1 is a perspective view of an article carrier bracket showing my new design in conjunction with a portion of an article carrier which is shown in broken lines for illustrative purposes only;

FIG. 2 is a side elevational view thereof;

FIG. 3 is a rear elevational view thereof;

FIG. 4 is a side elevational view thereof in unlocked position; and

FIG. 5 is a front elevational view thereof.

The side opposite to that shown in FIGS. 2 and 4 is substantially plain and unornamented.

FIG. 1

FIG. 3

FIG. 4
